UNITED STATES PATENT OFFICE.

WILLIAM P. BROWN, THOMAS A. ERRETT, AND GEORGE McALPINE BRITTAINE, OF SAN FRANCISCO, CALIFORNIA.

CUTTING TIP FOR TORCHES.

Application filed June 10, 1920. Serial No. 388,070.

To all whom it may concern:

Be it known that we, WILLIAM P. BROWN, THOMAS A. ERRETT, and GEORGE McALPINE BRITTAINE, citizens of the United States, residing at San Francisco, in the county of San Francisco, State of California, have invented a new and useful Cutting Tip for Torches, of which the following is a specification in such full and clear terms as will enable those skilled in the art to construct and use the same.

This invention relates to a cutting tip for oxy-acetylene or oxy-hydrogen torches and its object is to produce a cutting tip which will effectually prevent the heating flames from snapping back into the torch or pipe line and interfering with the operation of the torch.

It will be understood by those skilled in the art that by the use of hydrogen or acetylene that special kinds of tips or mixing devices are necessary to prevent the flame from striking back into the tip or even into the hose line itself and destroying the tip or destroying the hose line.

In the present invention means is provided to so direct the gas to the burner tip as to prevent the direct striking back of the flame because of the arrangement of holes in the burner tip.

Other objects of the invention will appear as the description proceeds.

An embodiment of the invention is shown in the accompanying drawings in which the same reference numeral is applied to the same portion throughout, but we are aware that there may be modifications thereof.

Figure 1 is a longitudinal sectional view of a cutting torch tip adjacent its end.

Fig. 2 is a transverse sectional view of the torch on the line 2—2 Fig. 1.

Fig. 3 is an end view of the torch looking from the lower portion of the sheet Fig. 1.

The numeral 1 indicates the handle of the torch through which the oxygen passageway 2 extends, another oxygen passageway 3 extends therethrough at the side of the passageway 2 and the hydrogen or acetylene gas passageway 4 lies at the side of the passageway 3.

The end of the handle 1 is chambered out to receive a frustoconical head 5, two annular grooves 6 and 7 surround it. One of said grooves to be positioned to cover the end of the hole 3 and the other of said

grooves to cover the hole 4. Smaller openings 8 and 9 extend through head 5 and connect the annular groove 6 with a flat annulus 10 at the wide end of the frustoconical head 5. Smaller openings 11 and 12 connect the grooves 7 with the holes 8 and 9. The burner tip 13 is held in place on the handle 1 by means of the annular nut 14 which engages the flange 15 and holds the tip in place. A small lug 16 on the flange 15 engages the end of the handle 1 and holds the burner tip in a fixed position, the object being to hold the two holes 17 and 18 out of the line with the two holes 8 and 9.

In the present instance the burner tip 13 is shown with two of the mixed gas openings and with a center hole 20 which is aligned with the hole 2 when the burner is ready for use so that the oxygen can pass directly through the center hole without coming in contact with an inflammable gas until it leaves the burner tip.

In operation whenever the gas strikes back owing to the slowing up of the velocity at the end of the burner tip, it strikes against a solid wall of the cone 5, the change in direction of the gases in passing from the holes 8 through the annular chamber 10 to the holes 17 and 18 preventing the flame from striking back any further than the chamber 10.

It will also be observed that the holes 8 and 9 are smaller in diameter than the holes 17 and 18, so that there is a change in pressure from the holes 8 and 9 to the chamber 10 as well as a different change in pressure from there to the holes 17 and 18, whereby the tendency of the gases to strike all the way back into the hose, is interfered with because of the difference in pressure of the gases in these three different spaces.

What we claim is as follows, but various modifications may be made in the construction shown in the drawings and above particularly described form, within the purview of our invention:

An oxy-acetylene cutting torch, comprising a nozzle holder having three passageways extending therethrough, a frusto-conical mixer seated in the end of said nozzle holder and having an opening adapted to align with one of the openings of the nozzle holder, said frustoconical member having two peripheral grooves with which the ends of two of the holes through the nozzle

holder connect, and also having a groove at one end to form an annular chamber around the central opening, openings leading from the peripheral opening in the frusto-conical member to the annular groove in its face, and a nozzle secured to the nozzle holder, having three holes therein, one of said holes being in alignment with the aligned holes of the mixer and the nozzle holder, and the other two of said holes being substantially at 90 degrees to the gas supply holes leading

from the peripheral openings in frusto-conical mixer to the annular openings adjacent the nozzle, whereby the striking back of gas is prevented.

In testimony whereof we have hereunto set our hands this 1st day of June A. D. 1920.

WILLIAM P. BROWN.
THOMAS A. ERRETT.
GEORGE McALPINE BRITTAIN.
